Specification for Design.

Patented May 7, 1912.

Application filed November 28, 1911. Serial No. 662,928. Term of patent 3½ years.

To all whom it may concern:

Be it known that I, THOMAS L. LAWTON, a citizen of the United States, residing at Philadelphia, in the county of Philadelphia and State of Pennsylvania, have invented a new, original, and ornamental Design for Rugs, of which the following is a specification, reference being had to the accompanying drawing, forming part thereof.

The figure of the drawing is a plan view

of a quarter section of a rug, the other three quarters being repeats thereof, showing my design.

I claim:

The ornamental design for a rug as shown.

THOMAS L. LAWTON.
